UNITED STATES PATENT OFFICE.

JULES CORNU AND PAUL CORNU, OF LISIEUX, FRANCE.

FLYING-MACHINE.

No. 902,859.

Specification of Letters Patent.

Patented Nov. 3, 1908.

Application filed September 11, 1906. Serial No. 384,171.

To all whom it may concern:

Be it known that we, JULES CORNU and PAUL CORNU, citizens of the Republic of France, residing at Lisieux, Calvados, 5 France, have invented certain new and useful Improvements in Flying-Machines, of which the following is a specification.

This invention relates to a flying machine in which the volume of air displaced by the 10 propelling and supporting part, such as a screw propeller or a turbine, is utilized by acting on planes arranged at an adjustable angle below, or at the back of, the said part, for the purpose of either only propelling the 15 machine, or both of propelling and supporting it.

A flying machine or apparatus according 20 to this invention also comprises a pendulum system which enables the equilibrium to be automatically insured; a device enabling the 25 adjustable propelling planes to be utilized for steering and turning; and finally, driving gear which enables several screw propellers to be driven by means of a single endless belt.

In the accompanying drawing: Figure 1 shows diagrammatically an elevation of a flying apparatus embodying the invention in 30 which the inclined propelling planes are arranged below screw propellers rotating horizontally and acting as supporting parts. Fig. 2 shows diagrammatically the same apparatus in end elevation. Fig. 3 is an end elevation of another construction of such an 35 apparatus, in which a vertically rotating screw-propeller, acting as a propelling part, is combined with inclined planes which in this case support the apparatus. Fig. 4 is a diagrammatic view in elevation of a construction of the apparatus shown in Fig. 1, and provided in addition with devices for 40 automatically maintaining the equilibrium, for steering by means of the adjustable planes and for driving by means of a single belt, 45 the apparatus being shown in a normal working position. Fig. 5 is a plan corresponding to Fig. 4 and showing more particularly the arrangement of the propelling planes for 50 steering in a straight line. Fig. 6 is a view similar to that shown in Fig. 4, the apparatus being shown in an inclined position. Fig. 7 is a plan corresponding to Fig. 6, the 55 steering part being in the position required for turning. Fig. 8 is a partial elevation of the apparatus shown in Figs. 4 to 7, chiefly showing the driving gear. Fig. 9 is a plan

corresponding to Fig. 8, the metal frame and the screw propellers being removed.

According to the construction shown in Figs. 1 and 2, the apparatus comprises one or more screw propellers *a* with vertical spindles, rotating in the cross beams of a frame *b* which is secured to the frame carrying the motor and the aeronauts. Below the said propellers, that is to say, near their driving surface, are arranged planes *c* of a length equal to the diameter of the propellers, mounted at the ends by means of hinge pins *d*, suitably guided by and connected to levers *e* pivoted centrally on pins *f* secured to the frame *b*; the whole of the planes *c* forms a kind of louver with pivoted blades, the inclination of which can be modified by means of a lever *g* secured to the pivot pin of the central lever *e*. The said lever *g* is provided with a locking device coöoperating with a segment or quadrant *h* for maintaining the planes *c* in any desired position. The said lever *g* could, of course, be replaced by any other suitable part, capable of bringing about the inclination of the planes *c* in the two directions. The planes *c* leave between them intervals through which the air, driven under pressure by the propellers *a*, is forced to pass.

The working is as follows:—Taking the apparatus at the moment of starting, the planes *c* are then in a vertical position. The propellers *a* being operated by the motor, the whole apparatus rises vertically, the planes *c* offering to the current of air produced by the propellers *a* only their edges, so that they do not offer any obstacle to the propulsion and do not absorb any ascensional power. The apparatus having been caused to rise, if it is desired to advance, while keeping on the same level, it is sufficient to incline the planes *c* so that the current of air produced by the propellers, should act on them and drive them in the direction of the arrow, Fig. 1, in the same way as the air acting on the blades of a windmill, with the difference, however, that the advance is in a straight line, instead of being circular. In this construction of the apparatus, the steering may be effected by a rudder *i* of suitable construction. By manipulating the planes *c*, the following different phases of the working of the apparatus can be obtained. 1. The planes *c* being in vertical position, the thrust of air on the same is equal to zero, and the propellers act alone

and raise the apparatus. 2. The planes *c* being inclined, their action brings about the propulsion of the apparatus, the speed of the horizontal movement of which will vary 5 according as their inclination is greater or less, the apparatus being at the same time supported by the working of the propellers. 3. The planes *c* being placed in such manner as to close the passage to the air displaced 10 by the propellers *a*, the ascensional effort of the said propellers will be counteracted, and the apparatus will descend like a parachute. 4. The planes *c* being inclined in the position opposite to that considered above under clause 15 2, they first act as a brake and then drive the apparatus backwards, thus forming a reversing gear. All the above results are obtained without modifying in the least either the speed, or the direction of rotation, 20 of the propellers.

In the construction of an apparatus according to this invention shown in Fig. 3, the pivoted planes *c* are arranged at the back of one or more propellers *a* rotating vertically, that is to say, having horizontal spindles. This arrangement enables the thrust of the propellers on the air to be simultaneously utilized for supporting and propelling the apparatus.

30 The construction shown in Figs. 4, 5, 6 and 7, first of all, comprises a device for enabling the equilibrium of the apparatus during its working to be automatically insured. This device or system consists in arranging below the supporting propellers *a*, either behind the adjustable planes *c* or in frames independent of those of the adjustable planes *c*, blades *j* which are normally arranged at a right angle to the longitudinal axis of the apparatus, and mounted on the sides of their supports *k*, *l*, so as to pivot at the ends, in the center of their width. The said blades *j* are connected together at their longitudinal edges by rods, chains or 45 cables *m* *n* constituting, with the transverse sides of the said blades *j*, a kind of parallelogram with multiple elements hinged to each other.

One of the cables, the cable *m*, is connected to the pendulum rod of a weight *o* suspended to the frame *p*, the other cable *n* being connected to a spring *r* having a tendency to bring the blades *j* back into their initial position, that is to say, into a position at right angles to the horizontal plane of the frames *k* *l* forming their brackets or supports. Stops *q* enable the said blades *j* to be maintained in their initial position against the action of the springs *r*. The 60 working of this pendulum device is as follows.

The apparatus being arranged horizontally as shown in Fig. 4, the weights *o* are at right angles to a horizontal plane passing through the two frame *k* *l*. It follows

therefrom that the chains connecting respectively the said weights to the corresponding blades *j* of the said frames, do not exercise any traction on the blades which remain vertical and at right angles to the 70 said frames. In this position when the propellers *a* are rotating, the air driven by them passes freely through the blades *j* without any action on the latter, but acts merely on the adjustable planes *c* for the purposes 75 of propulsion.

If the apparatus is inclined as shown in Fig. 6, the weights *o* having the tendency to maintain their pendulum rods in vertical position, one of them will pull the corresponding chain *m*, the result of which will be that the blades *j* situated at that end of the apparatus which is the highest at that moment, will be inclined. During this action, the blades *j* on the opposite frame remain at a right angle to it, owing to the action of the corresponding spring which keeps them against the fixed stop *q*.

The blades *j* which are inclined, form then on their frame, a panel with intervals 90 of a greater or smaller section, which afford passage only to a portion of the air driven by the corresponding propeller, so that, the raising power of the said propeller being reduced, the raising of the corresponding 95 end of the apparatus is delayed relatively to the other end, at which the air, driven by the propeller situated at that side, does not meet any resistance from the blades *j* which remain straight. This difference in the raising action of the propellers *a* results, therefore, in raising the end of the apparatus which at that moment is the lowest, and in thus automatically reestablishing longitudinal equilibrium of the said apparatus by the 100 working of the pendulum weights *o*.

Although the special shape of the whole frame carrying the parts of the apparatus tends normally to preserve transverse equilibrium, the said equilibrium might also be 105 insured by means of some device with blades, automatically inclined by pendulum weights. In that case, the blades would work in frames arranged at each side of the central vertical plane of the apparatus.

A single pendulum weight mounted by means of a ball joint in the center of the apparatus, could simultaneously operate the blades arranged at the front and at the back 115 of the apparatus, as well as at the sides.

The system of blades *j* exposed to the action of the pendulum weights *o* acts independently of the gear which operates the planes *c* as desired.

The construction of apparatus shown in 125 Figs. 4 to 7, also comprises a device enabling the adjustable propelling planes *c* to be utilized for steering the apparatus. This device consists in pivoting the frames *k* *l* to which the blades *c* *j* are pivoted, about the sockets 130

in which rotate the spindles of the propellers *a*. By this arrangement by connecting the frames *k l* by levers *s t* and a rod *u* crossing the longitudinal sectional plane of the apparatus, a horizontal oscillating movement may be simultaneously transmitted to the said frames *k l* by any desired means. The working of this steering device is as follows:—

- 10 The two frames *k l* being positioned as a continuation of the axis of the apparatus, as shown in Fig. 4, the traction produced by the adjustable planes *c*, is rectilinear, and the steering is effected in a straight line. In 15 order to turn, it is sufficient to act on the rod *u* so as to pivot the two frames *k l* towards the same side of the apparatus, as shown in Fig. 6. The air driven by the propellers *a*, acting then on the said planes *c* in 20 an oblique direction relatively to the central plane of the apparatus, the result will be that the latter will be given a turning propelling movement.

The suspension of the pendulum weights 25 *o*, as shown in Figs. 4 and 6, under the hinge pins of the frames *k l*, enables the said weights, as well as the blades *j* operated by them, to be independent of the steering movement transmitted to the said frames *k l*. It 30 is not absolutely indispensable that both frames *k l* should be hinged for the purpose of steering, it will be sufficient to pivot only one of them, either that in front, or that at the back, the other one remaining fixed. 35 Moreover, the equilibrium blades *j* may be controlled by the aeronaut at will, the object of the pendulum weights *o* being merely to straighten the apparatus automatically.

The construction of apparatus shown in 40 Figs. 8 and 9, comprises a driving gear which enables several propellers to be operated by a single endless belt. This system consists in the rotary movement being imparted to the two propellers *a* with vertical spindles 45 by a single crossed endless belt *v*, one of the halves of which after having passed over the corresponding guide pulleys *x* and *y* with horizontal spindles, passes round a driving pulley *z* operated by a suitable 50 motor.

One of the guide pulleys, either *x* or *y*, is mounted on a pivoted hand lever *w* which acts as a stretching gear, in order to enable the belt *v* to be stretched or slackened, and 55 consequently the motor to be thrown in and out of gear.

The driving gear parts are supported in their given relative working positions, by a metal frame connected to the frame *p* and 60 constructed to suit the power and type of the motor.

The special arrangement of the crossed belt *v* enables the pulley *z*, and the driving parts driving the same, to be arranged in the vertical central plane of the apparatus, 65 whereby perfect steadiness of the latter is insured. Moreover, this arrangement enables rotary movement to be imparted to the propellers *a* in opposite directions by means of their respective pulleys, whereby all gy- 70 rating movement of the whole of the apparatus is obviated, and its support or propulsion insured. In addition to the above mentioned advantage, this gear enables the propellers to be driven with a constant speed, in 75 spite of any slip that might take place on the driving pulley. Moreover, this system enables shocks to be avoided at starting.

The relative positions of the motor, propellers *a* and guide pulleys *x y* may, of 80 course, be varied, the essential point being that the axes of the motor and those of the said guide pulleys *x y* should be horizontal, and those of the propellers *a* vertical.

What we claim as our invention and de- 85 sire to secure by Letters Patent is:—

1. In a flying machine and in combination a propeller, means to rotate the same, a series of planes arranged relatively to the propeller across and at right angles to the path of 90 the air currents set up by said propeller, means to vary the inclination of said planes relatively to said path in one direction to raise lower and propel the machine, and means to vary the inclination of said planes 95 in another direction to steer said machine.

2. In a flying machine and in combination a propeller mounted to rotate on a vertical axis, a series of planes beneath the propeller, means to vary the inclination of the planes 100 relatively to the propeller to raise lower and propel said machine and means to vary the inclination of some of said planes in another direction relatively to the propeller to steer the machine.

3. In a flying machine and in combination a frame, a propeller mounted therein to rotate on a vertical axis, a series of planes mounted below the propeller so as to be movable to vary their inclination horizontally 110 relatively to the propeller and a second series of blades automatically controlled so as to normally maintain for the purpose described a vertical position.

In testimony whereof we have signed our 115 names to this specification in the presence of two subscribing witnesses.

JULES CORNU.
